POWER TRANSMISSION

Ferris T. Harrington and Ralph L. Tweedale, Detroit, Mich., assignors to Vickers Incorporated, Detroit, Mich., a corporation of Michigan

Application July 13, 1939, Serial No. 284,206

7 Claims. (Cl. 60—52)

This invention relates to power transmissions and particularly to those of the type comprising two or more fluid pressure energy translating devices, one of which may function as a pump and another as a motor.

The invention is more particularly concerned with a hydraulic transmission system for operating a hydraulic press or analogous device.

Presses of this character are frequently provided with a surge tank at the top of the press and with the hydraulic control mechanism and pump also mounted at the top of the press either in or adjacent to the surge tank. In very large presses the necessary manual controls must be located within reach of the operator near the bottom of the press, and it has been common practice to provide an electric circuit for operating the control mechanism at the surge tank by means of push button switches located within reach of the operator at the bottom of the press and arranged to selectively energize solenoids which are connected to operate the hydraulic controls overhead.

It is also desirable in many press installations to provide for reversing the press platen when the operating pressure in the main cylinder reaches a predetermined peak value. In presses of this character a commonly used expedient is to provide a solenoid for pulling the hydraulic control member into pressing position which solenoid is energized by a momentary-contact, normally-open, push button switch and to provide a holding relay for the solenoid, the holding circuit of which is arranged to be opened by a pressure responsive electric switch when the main ram pressure builds up to the desired peak. The control operating solenoid is thus deenergized permitting a spring or other biasing means to throw the control over to platen reversing position. Usually a mechanical or other connection between the platen and the control is provided for shifting the control member to neutral position when the platen is fully returned.

Control circuits of this character have presented certain difficulties centering around the pressure switch and holding circuit. If the hydraulic control member happens to be a four-way valve, the sudden shifting of the same from its pressing position to its platen returning position at the time when the pressure switch opens the holding circuit causes a sudden release of the extremely large amount of energy which is stored in the main cylinder and causes deleterious shocks of great magnitude. One object of the present invention is to provide a hydraulic

power transmission system for operating a hydraulic press wherein these difficulties are avoided.

- This and other objects are accomplished by
- 5 the provision of a hydraulic control panel which may be positioned in or near the surge tank at the top of the press which incorporates within itself a pressure responsive reversing system which is operated entirely hydraulically so far
  - 10 as the operation of shifting the control member from pressing position to returning position is concerned and which still permits the use of electric push button controls positioned at the operator's station to provide the necessary manual control of the press. This is preferably accomplished by the provision of a holding circuit which is arranged to be initially energized by a starting push button, and when energized, to be electrically held, not for the duration of the
  - 15 pressing stroke, but for the duration of a complete cycle consisting of a pressing stroke and a returning stroke, and to then be deenergized by a suitable limit switch operated by the platen when it reaches its fully returned position.
  - 20 Since hydraulic presses are almost always manufactured to order with individual features to suit each user's requirements, it becomes desirable to standardize as many of the parts of the press as possible without sacrificing the
  - 25 manufacturer's ability to provide a press control system which will meet any user's requirements. Another object of the present invention is, therefore, to provide a hydraulic transmission system for operating a press wherein there is
  - 30 utilized a main control panel which may be selectively combined with auxiliary control panels of various types to provide either an electrically operated control system or a direct mechanically operated one.
  - 35 Another problem which arises in the construction of hydraulic presses concerns those of the type wherein a booster cylinder is provided for producing a positive rapid advance stroke of the press. It is desirable, of course, to have substantially the same speed during the rapid advance stroke and during the return stroke of the platen. This requirement has heretofore necessitated the
  - 40 use of a separate booster cylinder and a separate pull-back cylinder having substantially equal areas. It is an object of the present invention, therefore, to provide a power transmission system for a hydraulic press wherein a single differential area cylinder and piston may be utilized for acting both as a booster cylinder and as a pull-back cylinder while retaining substan-
  - 45
  - 50
  - 55

tially equal speeds on the rapid advance and pull-back strokes.

Further objects and advantages of the present invention will be apparent from the following description, reference being had to the accompanying drawings wherein a preferred form of the present invention is clearly shown.

In the drawings:

Figure 1 is a diagrammatic view of a hydraulic power transmission system embodying a preferred form of the present invention.

Figure 2 is a fragmentary view corresponding to a portion of Figure 1 showing an alternative construction.

Figure 3 is a diagrammatic view of the main and auxiliary control panels forming a portion of the circuit illustrated in Figure 1.

Figure 4 is a diagrammatic view of the alternative auxiliary control panel illustrated in Figure 2.

Figure 5 is a diagrammatic layout of the hydraulic circuit of Figure 2 with a tabulation of the positions of the various valves at different stages of the operating cycle.

Referring now to Figure 1, there is illustrated a press having a main cylinder 10 in which is slidably mounted a main ram 12 carrying a press platen 14. Secured to the top of the cylinder 10 is a combined booster and pull-back cylinder 16 having a differential piston 18 therein and connected to the main ram 12 by the rod 20. Mounted on top of the cylinder 10 is a surge tank 22 which encloses the cylinder 16 as well as a pair of surge valves 24 of any suitable construction.

A pump 26 which is shown as of the variable displacement, unidirectional delivery type is adapted to be driven by a suitable prime mover, such as an electric motor 28. The pump 26 is preferably flange-mounted in one wall of the tank 22, the motor 28 being supported outside the tank, but for convenience in illustration is shown at the lower part of the figure. A suction conduit 30 connects the suction port of the pump with the surge tank 22 while the delivery conduit 32 connects the delivery port of the pump with a main control panel 34.

A pump stroke regulator 36 is provided for shifting the yoke 38 of the pump toward neutral position in response to a predetermined increase in pressure in the delivery line. For this purpose the regulator 36 is connected by a conduit 40 with an auxiliary control panel 42. A drain conduit 44 also connects the regulator with the tank 22 through a tank conduit 46. It will be understood that where the pump 26, regulator 36 and control panels 34 and 42 are positioned in the tank 22 that the tank conduits 30, 44 and 46 may be omitted or at least be very short.

The main control panel 34 is provided with a pressure port 48 and a tank port 50 to which the conduits 32 and 46 are respectively connected. It is also provided with a booster cylinder port 52, a main cylinder port 54 and a pull-back cylinder port 56 which are connected with their respective cylinders by conduits 58, 60 and 62.

The auxiliary control panel 42 is provided with three push-type solenoids 64, 66 and 68 adapted to operate certain valves within the panel and which will be later described. An electric control circuit is provided for controlling the energization of the solenoids and comprises a normally-open, two-circuit, starting push button switch 70 which, when depressed, establishes a

connection from line L¹ to the solenoid 64 by a conductor 72 and thence to line L². The switch 70 also establishes a circuit from line L¹ by a conductor 74 to the solenoid 66 and thence to line L². The solenoid 64 is provided with a holding contactor 76 adapted when the solenoid is energized to establish a branch circuit from line L¹ through a normally closed limit switch 78, conductor 80, normally closed emergency stop switch 82, and conductor 84. This circuit is in parallel with the circuit 72 and when completed permits the release of the starting switch 70. The limit switch 78 is arranged to be opened by a cam 86 carried by the platen 14 when the platen reaches the upper limit of its return stroke. A normally open, momentary contact, emergency reverse switch 88 is adapted when depressed to establish a circuit from line L¹ by a conductor 90 to the solenoid 68 and thence to line L².

Referring now to Figure 3, the internal construction of the main panel 34 and the auxiliary panel 42 is there illustrated. The pressure port 48 of panel 34 is in communication by a conduit 92 with a relief valve 94 of any suitable type serving as a maximum pressure limiting valve in the main pump delivery line. The valve illustrated is similar to that described in the patent to Harry F. Vickers, 2,043,453, and operates to open a by-pass 96 leading to the tank port 50 whenever a predetermined pressure is exceeded in the conduit 92. The maximum pressure limiting action of the valve is controlled by a pilot relief valve 98 connected to the control chamber 100 of the valve 94.

The conduit 92 extends to a spring-loaded resistance valve 102 from which a conduit 104 extends. The valve 102 is adapted to maintain a predetermined small pressure difference between conduits 92 and 104 such that a small pressure is always available at the conduit 92 for the purpose of operating pilot control valves in the panel 34.

The conduit 104 extends to the pressure port 106 of a main four-way valve 108. Valve 108 is provided with a centering spring 110 of usual construction and is adapted to be shifted by the admission of pilot pressure to the end chambers 112 and 114 through pilot control conduits 116 and 118. The valve is illustrated in its central or neutral position. A conduit 120 extends from the tank port 50 of the panel 34 to a tank port 122 of the valve 108.

Cylinder ports 124 and 126 of valve 108 are connected to conduits 128 and 130. The former leads through a pressure responsive sequence valve 132, which is similar in construction to the relief valve 94, to the booster cylinder port 52. The valve 132 is adapted to open when a predetermined pressure exists in conduit 128 and, when open, to connect that conduit with a branch conduit 134 leading through a resistance valve 136 to the main cylinder port 54. A parallel branch conduit 138 extends through a check valve 140 permitting free flow from the port 54 to the port 52. The conduit 130 extends through a check valve 142 and through a pressure responsive foot valve 144 to the pullback port 56. The valve 144 is also similar in construction to the valve 94 and serves to normally close a by-pass conduit 146 in parallel with check valve 142. When the pressure in conduit 130 exceeds a predetermined value which may be slightly above the gravity load of the platen 14, the valve

144 will open permitting flow from port 56 to port 126 through the by-pass 146.

The spool 147 of valve 108 is provided with a cut-away land 149 which registers with port 124 in central position of the spool but is of insufficient width to block flow between ports 106 and 122 in this position. A blocking land 151 registers with port 126 in central position and seals this port. End lands 153 and 155 serve to isolate the end chambers 112 and 114 from any communication with the main ports of the valve and act as pistons for shifting the valve. A central bore 169 connects the spaces or opposite sides of land 151 permitting flow from port 126 to port 106 when the spool is shifted to the left.

For the purpose of operating the surge valves there is provided a branch conduit 157 leading from conduit 130 to a port 159. The latter is connected by a conduit 161 to the opening cylinders of the surge valves 24. A branch conduit 163 leads from conduit 134 to a port 165 and thence by a conduit 167 to the closing cylinders of surge valves 24.

The auxiliary control panel 42 comprises two pilot valves 148 and 150 for controlling the flow of fluid to the pilot connections 116 and 118 for the main four-way valve 108. The pilot valve 148 has a shiftable spool 152 normally spring pressed downwardly and adapted to be lifted by the solenoid 64 whenever the same is energized. The valve 150 has a spool 154 adapted to be shifted upwardly by the solenoid 66 when energized or downwardly by the solenoid 68 when energized. A spring-pressed detent arrangement 155 maintains the spool in either one of its two possible positions.

The valve 148 constitutes in effect an on-off valve for the supply of pilot fluid while the valve 150 is connected to operate as a four-way reversing valve. Accordingly the valve 148 is provided with a pressure port 156 which is connected by a conduit 158 with the pressure conduit 92 in the main panel 34. A second port 160 connects by a conduit 162 with the pressure port 164 of valve 150. The lower cylinder port 166 of valve 150 is connected to conduit 116. The upper cylinder port 168 is connected to conduit 118 which for sake of clearness is only partially illustrated in Figure 3. The lower tank port 170 of valve 150 is connected by a conduit 172 with a second conduit 174 leading to the tank conduit 120 in the main valve block. Conduit 172 extends beyond the port 170 by branch portions 176 and 178 to the tank port 179 and the lower end chamber 181, respectively, of the valve 148. The upper tank port 180 of valve 150 is connected by a conduit 182 with the conduit 128 in the main valve block which during the pressing stroke is under pressure and during the return stroke is connected to tank.

The upper end chamber 184 of the valve 150 serves as a pilot operating chamber to shift the spool 154 downwardly at the time of reversal of the press. For this purpose the chamber 184 is connected by a conduit 186 with the discharge port 188 of a pressure responsive valve 190 which may be similar in construction to the valve 94. The valve 190 is connected by a conduit 192 with the main cylinder port 54 of the main panel 34. Thus whenever the pressure in the main cylinder rises to a value determined by the setting of the pilot valve 196 of valve 190, pressure oil is admitted through conduits 192 and 186 to the pilot chamber 184 of valve 150. A branch conduit 198

is connected to the conduit 40 (see Figure 1) for actuating the pump regulator 36 at the same time that valve 150 is shifted downwardly.

For the purpose of permitting return flow from the chamber 184 when the spool 154 is lifted by solenoid 66, the conduit 186 has a branch 200 extending through a check valve 202 to conduit 192 and cylinder port 54. In order to insure against undesired slow shifting of valve spool 154 should there be any leakage through the valve 190, a branch conduit 204 connects the port 188 with the drain conduit 174 through a restriction 206 which is not sufficiently large to handle the entire discharge therefrom when the valve lifts.

For the purpose of introducing a variable time delay in the operation of reversing the press, the lower end chamber 208 of valve 150 is drained through an adjustable restriction 210 leading to the drain conduits 172 and 174. A check valve 212 permits free flow around the restriction 210 in the opposite direction when valve spool 154 is lifted by solenoid 66. The adjustable restriction 210 may be provided with a sprocket wheel 214 for remote adjustment adjacent the operator's station by means of a chain and sprocket drive 216 (see Figure 1). A similar chain and sprocket drive 218 may be provided for the adjusting screw 220 for the pilot valve 196 of the pressure responsive valve 190.

Since the valve 190 determines the pressure or tonnage at which reversal of the press takes place and since this tonnage requires adjustment for different jobs which a given press may be required to do, convenient means for adjusting the same are provided. Likewise the variable restriction 210 determines the length of dwell of the press before reversal takes place and requires frequent adjustment for various jobs. The adjustments for the pressure responsive valve 94, 132 and 144 normally do not require change after the press has been once set up.

In operation, starting with the position illustrated in Figures 1 and 3 with the motor 28 driving the pump 26, fluid is withdrawn from the tank through conduit 30 and delivered by the pump through the conduit 32 to port 48 of the main panel 34. The entire delivery of the pump is by-passed through resistance valve 102, conduit 104, port 106, and across the cut-away land 149 to port 122 from which the flow returns to tank through conduit 120, port 50 and conduit 46. The blocking land 151 locks the fluid trapped in the lower end of cylinder 16 from escaping to tank through conduit 62, port 56, and conduit 130. The check valve 142 and the pressure responsive valve 144 also prevent any outflow from the lower end of cylinder 16 except at a pressure sufficiently high to open the valve 144, which pressure is not created by the normal gravity load of the platen.

If now the starting switch 10 be depressed, solenoid 64 will be energized to lift valve spool 152, and solenoid 66 will be energized to lift valve spool 154. Under these conditions pressure fluid is delivered from conduit 92 ahead of the resistance valve 102 through conduit 158, ports 156 and 160, conduit 162, ports 164 and 168, and conduit 118 to the end chamber 114 of the main valve 108. The valve spool is accordingly shifted to the left blocking the by-pass path between ports 106 and 122 and admitting full pump delivery from conduit 104 to conduit 128 and through port 52 and conduit 58 to the head end of cylinder 16. The piston 18 and main ram 12 accordingly descend at a rapid rate, the surge valve 24 operating as

check valves and freely opening to admit oil from the surge tank 22 to the main cylinder 10.

Oil discharged from the lower end of cylinder 16 flows through conduit 62, port 56 and conduit 130 to valve 144. As soon as sufficient pressure is built up, valve 144 opens permitting the flow to continue through conduit 146 to port 126 and through the central passage 169 to joint with the pump delivery at port 106. Thus the entire discharge from the rod end of cylinder 16 is returned to the head end thereof making the effective area of cylinder 16 equal to the area of the rod 20 only. Thus if equal speeds on the rapid advance and return strokes are desired, the piston 18 is made with an area double that of the rod 20. At the time the valve spool 147 shifted to the left, oil was discharged from end chamber 112 through conduit 116, port 166, port 170, and conduits 172, 174 and 120 to tank.

As soon as the platen meets resistance sufficient to open the pressure responsive valve 132, the latter lifts admitting pressure oil to the conduit 134. Before the resistance valve 136 is opened, oil is admitted through branch conduit 163, port 165, and conduit 167 to the closing chambers of surge valves 24 thus positively closing the same. As soon as these valves are closed, pressure is built up further to open the resistance valve 136, thus admitting the pump delivery to the main cylinder 10 in addition to the cylinder 16.

The main pressing stroke, thus begun, continues until sufficient pressure builds up in the pump delivery line to open the valve 190. This pressure is transmitted from port 54 through conduit 192 to the valve 190 which then lifts admitting oil through conduit 186 to the pilot operating chamber 184 of valve 150. The latter is accordingly shifted downwardly at a rate determined by the setting of the adjustable restriction 210 which determines the rate at which oil can be discharged from the lower end chamber 208 to the tank.

At this point it may be noted that the solenoid 66 is no longer energized since the starting switch 70 will normally be released by the operator as soon as the platen 14 starts downwardly and lets cam 86 ride out from under the limit switch 78, thus permitting the latter to close. At this point the holding circuit 84 is now completed, thus permitting the solenoid 64 to remain energized without continued depression of the starting switch 70.

When the valve 150 is shifted fully downwardly, both end chambers 112 and 114 are momentarily connected to equal pressures. The chamber 112 is connected to full pump delivery pressure from conduit 92, through conduit 158, valve 148, conduit 162, ports 164 and 166, and conduit 116. Chamber 114 is connected to the same source of pressure from conduit 92, through resistance valve 102, conduit 104, valve 108, conduit 128, conduit 182, ports 180 and 168, and conduit 118. In this connection it will be noted that the resistance valve 102 has a substantial area which is exposed to the pressure in conduit 104 so that whenever the pressure in conduit 104 builds up to a significant value, the resistance valve 102 opens fully to impose no restriction on the flow therethrough. Thus the resistance valve operates as such only when the conduit 104 is at substantially zero pressure. Accordingly, since the pressures on both ends of the valve spool 147 are equal, even though high, the spring 110 takes

control and brings the spool to its central position.

At the time that pressure responsive valve 94 opened, pressure oil was also admitted through 6 conduit 186, branch conduit 198 and conduit 40 to the pump stroke regulator 36. The regulator piston accordingly is moved up to bring the adjustable yoke 38 of the pump nearly into neutral position. Thus, the rate of pump delivery is reduced to correspond with the requirements during the dwell at the end of the pressing stroke.

As soon as valve spool 147 approaches center position, the land 149 begins to open to flow from port 124 across to port 122. The tremendous energy which is stored in the main cylinder 10 is thus gradually relieved to tank through conduit 60, port 54, conduit 138, check valve 140, conduit 128, ports 124 and 122 and conduit 120 to tank. As soon as the pressure at port 124 is fully relieved which in actual practice requires only a fraction of a second, the pressure in end chamber 114 is relieved correspondingly, thus permitting the superior pressure in end chamber 112 to complete the movement of spool 147 to the right 25 to cause the return stroke of the press. Under these conditions pump delivery is directed from port 106 to port 126 and through conduit 130, check valve 142, port 56 and conduit 62 to the lower end of cylinder 16. The piston 18 is accordingly lifted discharging oil from the head end of cylinder 16 through conduit 58, port 52, conduit 128, ports 124 and 122 and conduit 120 to tank. Pressure oil from conduit 130 is also delivered through branch conduit 157, port 159, and conduit 161 to the opening chambers of surge valves 24 thus positively opening the same permitting oil to be displaced from main cylinder 10 back to the surge tank 22.

As soon as the platen reaches its fully returned position, cam 86 opens limit switch 78 thus de-energizing solenoid 64 permitting valve 148 to move downwardly under its spring bias cutting off the pressure supply from the end chamber 112 and connecting the same to tank through 40 conduit 116, ports 166 and 164, conduit 162, ports 160 and 179, and conduits 176, 172, 174 and 120. Since the right-hand end chamber 114 remains connected to tank as before, the spring 110 again brings the spool 147 to center position, the parts 50 having been thus restored to the position of rest.

If, while the platen is descending on a pressing stroke, an emergency condition should demand immediate reversal of the press, the emergency reverse switch 88 may be depressed to energize 55 solenoid 68, thus shifting the valve spool 154 downwardly before the full working pressure is built up in the press. Should it be desired merely to stop the press without reversal in the middle of a pressing stroke, the emergency stop switch 60 82 may be depressed, opening the holding circuit 84 for solenoid 64 and permitting the valve spool 152 to drop, thus shifting the valve 108 to neutral position in the manner previously described.

The four pressure responsive valves 94, 144, 65 132 and 190 have been described as similar to one another, but there are certain differences in their operating connections which should be pointed out.

The valve 94 has the discharge side of its pilot valve 98 connected to tank through the interior bore of the main valve 94. Thus the pilot valve 98 is responsive to pressure difference between control chamber 100 and tank. The valve 94 is arranged to be responsive also to the pilot valve 75 196 for pressure responsive valve 190 since it has

been found that this assists in obtaining a smooth reversal of the press and insures against momentary pressure peaks in the pump delivery line due to the small but appreciable time interval required for shifting the pump regulator 36. For this purpose a conduit 222 extends between the control chamber 100 and the inlet side of pilot valve 196 thus connecting together the control chamber of both valves 94 and 190. The adjustment of pilot valve 98 is normally the highest adjustment of any of the pilot relief valves in the system and serves merely as an over-all safety pressure limiting control in case of accidental derangement of the system.

The valves 132 and 144, since they discharge to passages which are not always at tank pressure, have their pilot valves arranged with their discharge sides connected to tank by drain conduits 224 and 226 which lead by a connection 228 to the tank conduit 120. Thus the valves 132 and 144 open when the pressure in their control chambers reaches a predetermined level above tank pressure which level is ordinarily relatively low compared to the opening pressures of valves 190 and 94. Since at the time these valves are open their discharge conduits 134 and 146 respectively connect to points of high pressure, it will be seen that the action of these two valves is to open wide as soon as they begin to lift and to remain open until the pressure in their respective discharge conduits falls below the value at which the valves opened.

The action of pressure responsive valve 190 is similar to that of valves 132 and 144 since its pilot valve 196 discharges to tank rather than to the main discharge port 188 of the valve 190.

In Figures 2 and 4 there is illustrated an alternative auxiliary control panel 230 which may be used in place of the control panel 42 for installations where electric push button control is not desired and a hand lever control is satisfactory. In the alternative panel 230 only a single valve 232 is provided which is arranged to combine the functions of valves 148 and 150. For this purpose the main pressure port 234 connects by a conduit 236 with the pump delivery conduit 92 in a manner analogous to the conduit 158. The cylinder ports 238 and 240 connect with the conduits 116 and 118 respectively. The lower tank port 242 connects with the tank conduit 172 while the upper tank port 244 connects with the conduit 182.

The spool 232 has its two middle lands provided with notches 248 which connect lines 116 and 118 with the tank ports 242 and 244 when the spool is in central position illustrated, the pressure port 234 being blocked. When the valve is shifted either upwardly or downwardly, the same connections are established as those established by the valve 150 previously described. The upper pilot operating chamber 250 corresponds with the operating chamber 184 and is connected with the conduit 186, the branch 198 being plugged where a fixed displacement pump is utilized for driving the system. The lower chamber 251 corresponds to the chamber 208 in Figure 3. The valve spool is provided at its upper end with the usual spring-loaded detent mechanism 252 for lightly retaining the valve spool in any of its three possible positions.

As shown in Figure 2, the alternative control panel 230 cooperates with the main panel 34 to provide a control for the main hydraulic circuit in the same manner as previously described in connection with Figure 1. In place of the vari-

able displacement pump 26 a fixed displacement pump 254 is illustrated as being connected in between the suction conduit 30 and the delivery conduit 32. The spool 232 may be operated by a depending rod 256 extending downwardly along side the platen and having a collar 258 adapted to be lifted by a projecting member 260 on the platen when the latter reaches the upper limit of its stroke. The lower end of the rod is connected for hand operation with a lever 262.

The operation of the device with the alternative auxiliary panel provided is the same as that previously described except that the operator manually depresses the lever 262 to raise the rod 256 and valve spool 232, thus establishing the same connections as those described when valve spool 154 is lifted. At the end of the pressing stroke when pressure builds up, the valve spool 232 is shifted downwardly in the same manner as was described for valve spool 154 thus reversing the press and shifting lever 262 to its fully up or reverse position. As the platen reaches the end of its return stroke the projection 260 engages the collar 258, thus lifting the rod 256 and spool 232 to center position in which both end chambers of the main valve are connected to tank through the slots 248.

Figure 5 is a diagrammatic layout of the hydraulic circuits shown using the alternative control panel 230 wherein the various valves are represented merely as circles with the flow conditions therethrough at various stages of the operating cycle being indicated in the table immediately below each valve.

While the form of embodiment of the invention as herein disclosed constitutes a preferred form, it is to be understood that other forms might be adopted, all coming within the scope of the claims which follow.

What is claimed is as follows:

1. In a hydraulic power transmission system for operating a press or the like the combination with a source of pressure fluid, and a reversible fluid motor of a main valve for controlling the direction of fluid flow to the motor and having a pair of pilot-operating chambers for selectively shifting the valve in opposite directions between forward and reverse positions, spring means for shifting the valve to a neutral position when the pressures in said chambers are equal, said valve in neutral position being arranged to exhaust one end of the motor, and pilot valve means for selectively directing pressure fluid from said source to either of said pilot-operating chambers and connected to simultaneously exhaust the other of said pilot-operating chambers, the exhaust line from one of said chambers being direct while the exhaust from the other pilot-operating chamber is connected to said one end of the motor whereby, when the pilot valve means is shifted to reverse the main valve, the main valve may be shifted to neutral position by said spring and momentarily prevented from shifting to reverse position until the pressure in said one end of the motor has been materially reduced.

2. In a hydraulic power transmission system for operating a press or the like the combination with a source of pressure fluid, and a reversible fluid motor of a main valve for controlling the direction of fluid flow to the motor and having a pair of pilot-operating chambers for selectively shifting the valve in opposite directions between forward and reverse positions, spring means for shifting the valve to a neutral position when the pressures in said chambers are equal, said valve

in neutral position being arranged to exhaust one end of the motor, pilot valve means for controlling the flow of fluid to and from said chambers to shift the main valve selectively to forward or reverse position, and means connecting said pilot valve means to said chambers and to said source and motor to provide momentarily balanced pressures in both the chambers when the pilot valve means is shifted to cause the main valve to shift to reverse position, whereby the main valve may be shifted to neutral position by said spring.

3. In a hydraulic power transmission system for operating a press or the like the combination with a source of pressure fluid, and a reversible fluid motor of valve means for controlling the direction of fluid flow to the motor, a separate valve for selectively causing the delivery of fluid from the source to the motor or interrupting such delivery, electric means including a holding circuit for operating the second valve to start a cycle of forward and reverse motor movements and to stop the motor at the end of the cycle, electric means for shifting the first valve means to cause a forward stroke of the motor, and hydraulic means responsive to pressure built up at the end of a forward stroke of the motor and acting directly on said first valve means for initiating a reverse stroke of the motor independently of either electric means.

4. In a hydraulic press of the type having a surge tank located near the top thereof the combination of a pump, and a directional flow control assembly mounted adjacent the tank, said control assembly including self-contained, electrically-actuated means for initiating, maintaining and terminating a complete cycle of operation including a pressing stroke and a return stroke, self-contained, hydraulically-actuated means for reversing the flow to the press in response to the building up of pressure at the end of a pressing stroke, self-contained, electrically-actuated means for reversing the flow to the press independently of pressure, and switch means positioned remote from the tank and adjacent an operator's station for controlling said electrically-actuated means.

5. In a hydraulic press of the type having a surge tank located near the top thereof the combination of a pump, and a directional flow control assembly mounted adjacent the tank, said control assembly including self-contained, electrically-actuated means for initiating, maintain-

ing and terminating a complete cycle of operation including a pressing stroke and a return stroke, self-contained, hydraulically-actuated means for reversing the flow to the press in response to the building up of pressure at the end of a pressing stroke, switch means positioned remote from the tank and adjacent an operator's station and a circuit for initially energizing said electrically-actuated means, a parallel circuit for maintaining said electrically-actuated means energized independently of said switch means, and a second switch means controlled by the return of the ram to its idle position for interrupting said parallel circuit.

15 6. A pressure regulating system for a hydraulic power transmission circuit having a pump, a hydraulic motor, a shiftable control member for determining the flow between the pump and the motor, and a pilot-controlled relief valve for bypassing the fluid delivered by the pump, said system comprising a servomotor for operating said member, a second pilot-controlled relief valve for controlling the flow of fluid to operate said servomotor, a pilot relief valve and means connecting said pilot relief valve to both pilot-operated relief valves for joint control thereof.

7. In a hydraulic power transmission system for operating a press or the like the combination with a source of pressure fluid, and a reversible fluid motor of means for controlling the direction of fluid flow to the motor including a valve arranged to exhaust one end of the motor in neutral position of said means, and pilot control mechanism for shifting said means to a first position in which pressure fluid is directed to said one end of the motor, and to a second position in which pressure fluid is directed to the opposite end of the motor, said pilot control means including a fluid pressure connection 30 from the pump effective to cause shifting to said second position, another fluid pressure connection to said one end of the motor effective to oppose such shifting, and means for centering said first-named means in neutral position when pressures 35 in both connections are acting in opposition to one another, said other connection acting to prevent shifting past neutral position until the pressure in said one end of the motor has fallen to a predetermined value by exhausting through said 40 valve.
